UNITED STATES PATENT OFFICE.

MOUBRAY GORE FARQUHAR, OF ABOYNE, SCOTLAND, AND ARTHUR HENRY HILL, OF BIRMINGHAM, ENGLAND.

AUTOMATIC FIREARM.

No. 920,301.

Specification of Letters Patent.

Patented May 4, 1909.

Application filed December 2, 1908. Serial No. 465,596.

To all whom it may concern:

Be it known that we, MOUBRAY GORE FARQUHAR and ARTHUR HENRY HILL, subjects of the King of the United Kingdom of 5 Great Britain and Ireland, and residing at Aboyne, Aberdeenshire, Scotland, and Birmingham, Warwickshire, England, respectively, have invented a certain new and useful Improvement in Automatic Firearms, 10 of which the following is a specification.

This invention relates to automatic firearms of the kind referred to in patent specification No. 867,960 and has for its object to provide simplified and less expensive means 5 whereby the energy of the recoil of the barrel shall be conserved and the breech shall not be opened until all pressure has left the barrel.

In this invention, as in that described in 0 the specification of the above mentioned patent, there are two principal movements (1) the recoil of the barrel, with the bolt still in position locked, and the return to the firing position and (2) the release of the 5 spring, (which has been brought into tension by the recoil of the barrel), operating the bolt.

In the accompanying drawings Figure 1 is an elevation of part of a rifle constructed in accordance with the invention, the wooden work of the rifle being removed for the sake of clearness. Fig. 2 is a part elevation and part vertical section of the rifle as viewed from the opposite side. Fig. 3 is a cross section on the line X—X, Fig. 2. Fig. 4 5 shows a modified construction.

As shown particularly in Figs. 1, 2 and 3, there is attached to the barrel A a toothed rack B, which rack gears with and rotates a toothed wheel C when the barrel A recoils. To the outside of said wheel C is attached a larger toothed wheel D which is adapted to gear with a movable toothed rack E, which rack E is mounted on a movable carrier F, said rack and carrier being supported on a ledge f formed on a stationary tubular casing I adapted to be carried by the rifle body. The rack E is free to move forward upon the carrier F; but, if the rack E be moved toward the breech, the carrier F is brought back also, by means of the end e of the rack E engaging an upturned flange f^o on the carrier F. The carrier F is attached at its front or muzzle end, as at f¹, to a block G which block G is in contact with a helical spring H located within the stationary casing I, so

that when the carrier F is moved rearward the spring H is compressed in that direction; the end portion of the carrier which is attached at f¹ to the block G being arranged to work in a slot i in the casing I.

Two studs or catches J, J¹, are provided, one stud J being pivoted at J^x and adapted to hold a washer j in engagement with the rear end of the spring H as the movable rack E and carrier F are being brought back, while the other stud J¹, which is pivoted at J¹¹ between jaws J¹² on the casing I and which has a cushion spring J¹³ at its end, is adapted to hold the block G of the carrier at the point g (and therefore the front end of the spring H) when said spring H has been brought back to its fullest extent by the action of the wheel D; said stud or catch J¹ being retained in normal position by a light spring J¹⁴. When the barrel A recoils against the action 75 of the return spring A¹, the rack E and its carrier F are brought back, the coil spring H is compressed and both of said studs or catches J, J¹ are projected and hold the spring H in compression; the stud J being actuated by a projection A² on the barrel A in advance of the stud J¹, which stud J¹ is actuated by a projection A³ on the barrel A; said projection A³ contacting with the cushion spring J¹³ and causing the stud J¹ to rock 80 on its pivot against the action of the spring J¹⁴, whereby the nose J¹⁵ of the stud J¹ engages with the block G at the point g and is retained in engagement by the reactionary pressure of the spring H on the inner end of 90 the block G. The barrel A then returns forward to the firing position against the stop a, the toothed wheel D is rotated in a contrary direction, and the movable rack E is carried forward, also leaving behind its carrier F and the spring H in compression; these being held by the said studs J, J¹.

As soon as the barrel A has returned forward to the firing position, the stud J which holds the rear end of the spring H is withdrawn by means of a projection a² whereupon the rear end of the spring H moves quickly back, opens the bolt K by means of a connecting rod L (shown particularly at Fig. 4) and compresses a light spring M which surrounds a rod l and abuts between the inner end of the casing I and the outer end of a sleeve N, while said rod L is connected to a pin n attached to the inner end of the sleeve N and passes through a slot i¹ (see Figs. 3 110

and 4) in the casing I. The stud J¹ is now withdrawn and the light spring M closes and locks the bolt K, also returning the coil spring H and carrier F to their normal position as shown, said stud J¹ being withdrawn by means of the spring J¹⁴ when the reactionary pressure of the spring H on the inner end of the block G has been relieved by the withdrawal of the catch J.

10 The construction shown in Fig. 4 is similar to that illustrated in Figs. 1, 2 and 3, except that the movable rack and carrier and corresponding gear wheels for compressing the spring H are dispensed with, and the compression of said spring H is effected by the direct action of the recoil of the barrel A by extending the projection A³ on the barrel into the casing I and in front of the spring H.

Having now described our invention what 20 we claim and desire to secure by Letters Patent of the United States is:—

1. In an automatic fire-arm, the combination with the barrel, and the bolt, of a spring adapted to be compressed by the recoil of the barrel, a second spring also adapted to be compressed by the recoil of the barrel, a catch device adapted to engage one end of the second spring when compressed, a second catch device adapted to engage the other end 25 of said second spring, means for disengaging the second catch on the return movement of the barrel whereby the second spring is free to open the bolt, means for disengaging the first catch when the second spring is relieved, 30

and a third spring compressed by the extension of the second spring, said third spring acting to close the bolt and to return the second spring to normal position. 35

2. In an automatic fire-arm, the combination with the barrel, and the bolt, of a helical 40 spring adapted to be compressed by the recoil of the barrel, a fixed tubular casing a second helical spring within said casing said spring also adapted to be compressed by the recoil of the barrel, a catch device carried by 45 said casing and adapted to engage one end of the second spring when compressed, a second catch device also carried by said casing and adapted to engage the other end of said spring, means for disengaging the second 50 catch on the return movement of the barrel whereby the second spring is free to open the bolt, means for disengaging the first catch when the second spring is relieved, a tubular sleeve within the casing, and a third spring 55 within the sleeve and compressed by the extension of the second spring, said third spring acting to close the bolt and to return the second spring to normal position.

In testimony whereof we have signed our 6 names to this specification in the presence of two subscribing witnesses.

MOUBRAY GORE FARQUHAR.
ARTHUR HENRY HILL.
